CLAIM

The ornamental design for a tower grater, as shown and described.

DESCRIPTION

FIG. 1 is a top perspective view of a tower grater showing our new design;

FIG. 2 is a bottom plan view thereof;

FIG. 3 is a top plan view thereof;

FIG. 4 is a front elevation view thereof;

FIG. 5 is a rear elevation view thereof;

FIG. 6 is left side elevation view thereof;

FIG. 7 is a right side elevation view thereof;

FIG. 8 is an exploded top front perspective view thereof showing the lower cartridge drawer with three sides and a bottom side;

FIG. 9 is an exploded front elevation view of the view of FIG. 8;

FIG. 10 is a bottom plan view of the upper grater part;

FIG. 11 is a top plan view of the upper grater part;

FIG. 12 is a rear side elevation view of the lower cartridge part;

FIG. 13 is a left side elevation view of the lower cartridge part;

FIG. 14 is a right side elevation view of the lower cartridge part;

FIG. 15 is a bottom plan view of the lower cartridge part;

FIG. 16 is a top plan view of the lower cartridge part; and,

FIG. 17 is a bottom perspective view of the upper grater part and lower cartridge part.

(Continued)

The broken lines shown in the figures depict portions of the tower grater that form no part of the claimed design.
